US00D997730S

(12) **United States Design Patent** (10) **Patent No.:** **US D997,730 S**
Wadsworth et al. (45) **Date of Patent:** **** Sep. 5, 2023**

(54) **CONTAINER**

- (71) Applicant: **Hydrojug, Inc.**, Ogden, UT (US)
(72) Inventors: **Hayden Wadsworth**, Ogden, UT (US);
Jeffrey Steel, Midland Park, NJ (US);
Matthew Earl Meyer, Bountiful, UT (US)
(73) Assignee: **HYDROJUG, INC.**, Ogden, UT (US)
(**) Term: **15 Years**
(21) Appl. No.: **29/804,396**
(22) Filed: **Aug. 19, 2021**
(51) **LOC (14) Cl.** **07-01**
(52) **U.S. Cl.**
USPC **D9/531**; D7/536
(58) **Field of Classification Search**
USPC D9/530, 531, 528, 537, 540, 542, 543,
D9/549, 550, 575, 434, 563, 499, 520;
D7/509, 510, 533; D3/202
CPC B65D 21/0231; B65D 1/0246; B65D
2501/0081

(57) **CLAIM**

The ornamental design for a container, as shown and described.

DESCRIPTION

FIG. 1 is a first perspective view of the container;

FIG. 2 is a second perspective view thereof;

FIG. 3 is a first side view thereof;

FIG. 4 is a second side view thereof;

FIG. 5 is a third side view thereof;

FIG. 6 is a fourth side thereof;

FIG. 7 is a top view thereof; and,

FIG. 8 is a bottom view thereof.

The dashed lines depict portions of the container that form no part of the claimed design.

1 Claim, 8 Drawing Sheets
